ATTORNEY.

UNITED STATES PATENT OFFICE.

WILLIAM WILKINSON, OF PHILADELPHIA, PENNSYLVANIA.

DESIGN FOR A HEATER, WATER, OR STEAM PIPE.

SPECIFICATION forming part of Design No. 21,561, dated May 24, 1892.

Application filed February 8, 1892. Serial No. 420,788. Term of patent 14 years.

To all whom it may concern:

Be it known that I, WILLIAM WILKINSON, a citizen of the United States, residing in the city and county of Philadelphia, State of Pennsylvania, have invented and produced a new and original Design for a Heater, Water, or Steam Pipe, of which the following is a specification, reference being had to the accompanying drawing, forming part thereof.

- 10 The leading feature of my design for a heater, water, or steam pipe is a cylindrical tube having a surface ornamentation of pyramidal figures of square bases, having their apexes in lines parallel with an axial or longitudinal line of the said pipe.

In the drawing, A designates a heater, water, or steam pipe. On the surface of the pipe are raised pyramids B, which join each other and have their sides formed by the bisecting oblique lines C C. The pipe at what may be termed its "sides" presents a zigzag appearance, as at D D.

I claim—

The design for a heater, water, or steam pipe, substantially as herein shown and described.

WILLIAM WILKINSON.
